UNITED STATES PATENT OFFICE.

ALBERT Y. TUCKER, OF MOUNT VERNON, NEW YORK.

DESIGN FOR A TIRE.

49,753.

Specification for Design.

Patented Oct. 10, 1916.

Application filed January 5, 1916. Serial No. 70,539. Term of patent 14 years.

To all whom it may concern:

Be it known that I, **ALBERT Y. TUCKER**, a citizen of the United States, residing at Mount Vernon, county of Westchester, and State of New York, have invented a new, original, and ornamental Design for Tires, of which the following is a specification, reference being had to the accompanying drawing, forming a part thereof.

The figure is a perspective view of a tire showing my new design.

I claim:

The ornamental design for a tire as shown.

Signed at New York, N. Y., this thirteenth day of December, 1915.

ALBERT Y. TUCKER.
